E. A. VOLLMERS

COLUMN INDICATING DEVICE FOR COPYHOLDERS

Filed Sept. 8, 1922

Inventor,
Emma Agnes Vollmers.

By Carl T. Ragan

Attorney

UNITED STATES PATENT OFFICE.

EMMA AGNES VOLLMERS, OF WHITE PLAINS, NEW YORK.

COLUMN-INDICATING DEVICE FOR COPYHOLDERS.

Application filed September 8, 1922. Serial No. 588,882.

To all whom it may concern:

Be it known that I, EMMA AGNES VOLLMERS, a citizen of the United States, and a resident of White Plains, in the county of 5 Westchester and State of New York, have invented certain new and useful Improvements in Column-Indicating Devices for Copyholders, of which the following is a specification.

- 10 My invention relates to position indicating devices and especially to devices of such a character as to be of assistance to copyists in copying columns of tabulated figures or other similar subject-matter.
- 15 In its preferred form, my invention relates especially to devices which are adapted for placement upon the horizontal line-indicating bar of a copy holder adapted to hold the subject-matter to be copied in a vertical 20 or other convenient position.

In the drawings:

Figure 1 represents the preferred embodiment of the invention in front view with certain parts being shown in section broken 25 away;

Fig. 2 represents a simpler modified form of the invention;

Fig. 3 illustrates the manner of placement 30 of the position indicating device upon the line-indicator bar of a copy holder; and

Fig. 4 represents a cross sectional view of the device illustrated in Fig. 1, taken along the section line 4—4.

In the preferred form of the invention as 35 illustrated in Fig. 1, the main portion of the device is formed of somewhat flexible and preferably somewhat resilient thin sheet material, such as a good quality of cardboard, aluminum, brass or steel, and comprises a body portion A from which extend 40 downwardly three depending portions B, C and D, and from which extend upwardly a portion 1, the right-hand edge of which is adapted to serve as the indicator of the left-hand margin of the column of figures 45 or the like to which the device may be adjusted. The depending portions B, C and D on the device serve as is more clearly illustrated in Fig. 3 for the adjustable placement 50 of the device upon and in sliding contact with a horizontal line indicator such as is shown at X in Fig. 3 and is ordinarily made of thin sheet metal. In such placement the portions B and D may be placed beneath or behind the line indicator X while the central depending portion C may be

placed above or in front of the line indicator X, and may be provided with a knob as shown at 8 for the convenience of the operator in sliding or otherwise adjusting 60 the device upon and along the line indicator.

In the preferred form of the invention as shown in Fig. 1, in order to afford marginal adjustment so that the device may expose to view columns of figures or other data of different widths, a right-hand upwardly extending portion 2 of the device is mounted in slidable engagement with the body portion A and this device also may be provided with a knob as shown at 3 for convenience in adjustment. In the specific form of the invention this right-hand margin indicator or column block 2 as shown in Fig. 1 may also be formed of sheet material such as is used 75 for the manufacture of the main body of the device and is provided with a central downwardly extending portion E which is adapted for placement in engagement with and behind the upturned forward portion of 80 a guide-way 4 which may be formed as shown in the drawing by the bending downwardly and then upwardly of a portion of the material integral with the body portion A. The column block 2 is also provided with downwardly extending portions as indicated at 85 5, 7 and 9, the portions 7 and 9 being adapted for engagement at their upper portions with the upturned front flange of the guide-way 4 and being adapted to have their lower 90 portions turned backward and upward beneath the depending back portion of the guide-way 4 so as to secure or hold the column block 2 in slidable engagement with the guide-bar. The depending portion 5 is 95 adapted to constitute a stop bar which in connection with the column adjuster stop 6 projecting outwardly from the body portion A of the indicator serves to limit the movement to the right of the column block 2. 100

As will be apparent from the drawings and from the foregoing description the column block 2 may be adjusted by sliding along the guide-way 4 so as to expose to view between the two column blocks 1 and 2 the column of figures or other subject-matter which it is desired to have in view regardless of the width of the same. Thus if a vertical column of figures is to be copied the same may be fastened to the supporting plate Y of the copy holder shown in Fig. 3. The column indicator may be ad-

justed to expose the particular column desired and by movement of the line indicator bar and column indicator relative to the supporting plate carrying the subject-matter to be copied, the figures or other subject-matter constituting the column may be successively exposed to view for great convenience in copying or otherwise examining the same.

10 In Fig. 2 I have illustrated a modified and much simplified form of the invention adapted for use where the feature of adjustability of one of the column blocks is not essential. In this modified form the device may likewise be formed of cardboard, sheet steel or other suitable material and comprises a body portion 100, upstanding stationary blocks 101 and 102, the right and left-hand margins of which respectively are 15 adapted to indicate the left and right-hand margins of subject-matter to be exposed to view. From the body portion 100 extend depending portions 103, 104 and 105 corresponding as to general configuration and 20 function to the portions B, C and D and described in connection with the device illustrated in Fig. 1. The depending portion 104 may be provided with a knob 106 for moving the device along a line indicator. 25 If columns of subject-matter of only one width are to be dealt with in connection with using the device the modified form shown in Fig. 2 will of course suffice, but in dealing 30 variably or successively with columns of different widths the adjustable form as 35 shown in Fig. 1 will obviously be much to be preferred.

As will be apparent from the drawings the extensions such as shown at 103, 104 and 40 105 serving for attachment of the position indicator upon a line indicator bar of a copy holder or some of these extensions may be bent so as to lie in a plane parallel to and slightly spaced from the plane of the 45 main portion of the device. By thus offsetting the extension 104, for example, a convenient and secure engagement of the device with the line indicator bar is facilitated. Similarly in the form of the invention 50 illustrated in Fig. 1 the extensions of the adjustable column block 2 (by which the column block is secured to the guide-way 4) may be offset from each other or from the plane of the main upper portion of the 55 column block 2 and the upper portion of the column block lying above the guide-way 4 may itself be offset by bending backwardly along the line just above the guide-way so that it will lie in a plane substantially coincident with that of the stationary column 60 block 1.

I claim:

1. A position indicating device formed with a body portion of stiff sheet material, 65 one edge of said device being provided with

means for holding the device in removable engagement with the line indicator bar of a copy holder, and the opposite edge of the device being provided with a fixed extension and with a flanged portion carrying a 70 slideable extension substantially parallel with the fixed extension, said extensions being adapted to serve as column bounding devices with columns of different widths.

2. A position indicating device formed 75 with a body portion of stiff sheet material, one edge of said device being provided with integral means for holding the device in removable engagement with the line indicator bar of a copy holder, and the opposite edge of the device being provided with a fixed extension and with a flanged portion carrying a 80 slideable extension substantially parallel with the fixed extension, said extensions being adapted to serve as column bounding devices with columns of different widths.

3. A position indicating device formed 85 with a body portion of stiff sheet material, one edge of said device being provided with means for holding the device in removable 90 engagement with the line indicator bar of a copy holder, and the opposite edge of the device being provided with a fixed extension and with a flanged portion carrying a slideable extension substantially parallel with 95 the fixed extension, said extensions being adapted to serve as column bounding devices with columns of different widths, and said slideable extension being held upon the body portion of the device by interlocking flanges. 100

4. A position indicating device formed with a body portion of stiff sheet material, one edge of said device being provided with means for holding the device in removable engagement with the line indicator bar of a 105 copy holder, and the opposite edge of the device being provided with a fixed extension and with a flanged portion carrying a slideable extension substantially parallel with the fixed extension, said extensions being adapted to serve as column bounding devices with columns of different widths, and said slideable extension being held upon the body portion of the device by interlocking flanges 110 and said body portion and slideable extension being provided with coating stops to limit the sliding movement of the said extension. 115

5. A position indicating device adapted 120 for use as a column indicator, said device comprising at one of its edges a fixed extension and a slideable extension movable to and from said fixed extension and in substantial parallelism therewith, said slideable extension being held in adjustable attachment on the device by interlocking flanges. 125

6. A position indicating device adapted 130 for use as a column indicator on columns of different widths, said device being substantially flat and comprising a body portion of

resilient sheet material having two substantially parallel edges, one of which edges is provided with integral extensions adapted to straddle a thin line indicator bar of a copy holder in slidable frictional engagement therewith, and the other of which edges is provided with an integral fixed extension and with a slidably adjustable extension parallel with the fixed extension and movable to and from the latter in interlocking guideways formed by coacting flanges on the said body portion and on the slidable extension.

7. A position indicating device formed with a body portion of stiff sheet material,

one edge of said device being provided with means for holding the device in removable engagement with the line indicator bar of a copy holder, and the opposite edge of the device being provided with a fixed extension 20 and with an adjustable extension substantially parallel with the fixed extension and in interlocking slidable engagement with the said body portion, said extensions being adapted to serve as column bounding devices 25 with columns of different widths.

In witness whereof, I have hereunto signed my name to this specification on the fifth day of September, 1922.

EMMA AGNES VOLLMERS.
